UNITED STATES PATENT OFFICE.

PAUL REIMANN, OF NEW YORK, N. Y., ASSIGNOR TO M. LOWENSTEIN & SONS, INC.,
OF NEW YORK, N. Y., A CORPORATION OF NEW YORK.

DESIGN FOR A TEXTILE FABRIC.

Application filed December 2, 1922. Serial No. 4,465. Term of patent 3½ years.

To all whom it may concern:

Be it known that I, PAUL REIMANN, a citizen of Germany, and a resident of the city of New York, borough of Manhattan, in the county and State of New York, United States of America, have invented a new, original, and ornamental Design for Textile Fabric, of which the following is a specification, reference being had to the accompanying drawings, forming part thereof, in which

The figure shows one complete repeat of the design applied to a piece of textile fabric.

I claim:

The ornamental design for a textile fabric, as shown.

PAUL REIMANN.
